UNITED STATES PATENT OFFICE.

SIMON J. HARDING, OF HARRISBURG, PENNSYLVANIA, ASSIGNOR TO FRED D. HARDING, OF WEST BALDWIN, MAINE.

CAKE-CUTTER.

No. 848,823.

Specification of Letters Patent.

Patented April 2, 1907.

Application filed May 26, 1906. Serial No. 318,911.

To all whom it may concern:

Be it known that I, SIMON J. HARDING, a citizen of the United States, residing at Harrisburg, in the county of Dauphin and State of Pennsylvania, have invented a new and useful Cake-Cutter, of which the following is a specification.

- The invention relates to improvements in cake-cutters.
- 10 The object of the present invention is to improve the construction of cake-cutters and to provide a simple, inexpensive, and efficient cake-cutter adapted to cut a variety of forms.
- 15 A further object of the invention is to provide a reversible cake-cutter adapted to cut the cake-dough either round or scalloped and either with or without a central hole or opening.
- 20 Also the invention has for its object to provide a cake-cutter of this character in which it will be unnecessary to remove any of the parts when cutting any of the several forms and which may be quickly arranged for any of the said forms.

With these and other objects in view the invention consists in the construction and the novel combination of parts hereinafter fully described, illustrated in the accompanying drawings, and pointed out in the claims hereto appended, it being understood that various changes in the form, proportion, size, and minor details of construction within the scope of the claims may be resorted to without departing from the spirit or sacrificing any of the advantages of the invention.

In the drawings, Figure 1 is a longitudinal sectional view of a cake-cutter constructed in accordance with this invention. Fig. 2 is 40 a plan view of the same. Fig. 3 is a detail sectional view illustrating the manner of interlocking the central support with the outer or main cutter. Fig. 4 is a detail perspective view of the transverse support. Fig. 5 is a 45 plan view illustrating a modification of the invention.

Like numerals of reference designate corresponding parts in all the figures of the drawings.

50 1 designates an outer or main cutter consisting of a resilient cylindrical body having a smooth circular cutting edge 2 for cutting cake-dough in circular form. The cylindrical body is provided at its opposite edge

with a crimped or corrugated rim 3, soldered 55 or otherwise secured to the cylindrical body and adapted to cut cake-dough in circular form with scalloped edges.

The cylindrical body is provided at diametrically opposite points with bearing- 60 openings 4 and 5 for the reception of journals or pivots 6 and 7 of a transverse support 8, which preferably consists of a casting of brass or other suitable material. The pivot 7 is provided with an extended threaded portion 9, forming a screw and embedded in a handle 10, which extends from one side of the cylindrical body and which constitutes the handle of the cake-cutter. The transverse support 8 is provided with a central circular 65 portion 11, having a central circular opening 12 for the reception of an inner cylindrical cutter 13, which is secured at its inner end or edge 14 to the transverse support by any suitable means. The inner end or edge 14 70 is provided with an outwardly-projecting flange which engages one of the faces of the transverse support 8, and the said inner end of the central cutter 13 may be conveniently soldered to the support; but any other preferred fastening means may be employed.

75 The bearing openings or perforations are arranged equidistant of the edges of the outer or main cutter, and the transverse support 8 is reversible to bring the inner cylindrical cutter into either half of the outer or main cutter, whereby the cake-cutter is adapted to cut the dough into circular form with either a smooth or scalloped outer edge 80 and either with or without a central hole or opening. This operation is effected by simply reversing or changing the position of the pivoted transverse support and the inner cutter, which is carried by the same.

85 The transverse support is provided at its 90 ends with shoulders 15, located at opposite sides of the pivots 6 and 7 and adapted to engage an annular groove 16 of the outer or main cutter. The groove which forms upper shoulders may be provided only at the opposite 95 portions of the outer or main cutter contiguous to the bearing openings or perforations; but it is preferable to extend the groove entirely around the outer or main cutter, as the said groove forms an exterior 100 bead, which is of an ornamental character. The resilient cylindrical body is adapted to be compressed at opposite sides of the trans-

verse support to extend or expand the cylindrical body at and disengage it from the ends of the transverse support, which may then be readily rotated. The resiliency of the metal maintains the cylindrical body and the transverse support in their interlocked relation. The transverse support is provided at its ends with openings 17, which lessen the cost of the device by reducing the amount of material. However, the end portions of the transverse support may be left solid, as illustrated in Fig. 5 of the drawings. In this form of the invention the transverse bar or support 18, which carries a central cutter 19, is connected with the outer or main cutter by opposite pivots 20, piercing the outer or main cutter from the exterior thereof and suitably secured to the end portions of the transverse support 18. The pivots 18 are formed integrally with the handle 21, which is constructed of stout wire or other suitable material, and the latter is bent centrally to form a substantially U-shaped handle. The material is bent outward from the inner end of the handle to form opposite angular arms 22, which are provided with terminal pivots 20. The handle 21 is adapted to swing to either side of the outer or main cutter to reverse the transverse support 18 and the inner cutter 19. The outer or main cutter 23 is constructed the same as those heretofore described, and additional illustration of the same is therefore deemed unnecessary.

It will be seen that the device is simple, strong, and durable, and that it is adapted for cutting plain round cake, scalloped cakes, and doughnuts, and that the round and scalloped cakes may be cut either with or without a central hole or opening. Also it will be clear that it is not necessary to remove any part of the cake-cutter to arrange the same for cutting any one of the several forms herein explained and that the configuration of the cutting edges may be changed without affecting the operation of the reversible inner cutter.

Having thus fully described my invention, what I claim as new, and desire to secure by Letters Patent, is—

- 50 1. A cake-cutter comprising an outer or main cutter, and an inner pivotally-mounted reversible cutter.
- 55 2. A cake-cutter comprising an outer or main cutter having opposite cutting edges, an inner movably-mounted reversible cutter arranged within the outer cutter, and exterior operating means connected to the inner cutter to reverse the same and move the said inner cutter into and out of position for cutting and to arrange the same to coöperate with either of the cutting edges of the main cutter.
- 60 3. A cake-cutter comprising an outer or

main cutter having opposite cutting edges, an inner movably-mounted reversible cutter arranged within the outer cutter, and exterior operating means connected to the inner cutter to reverse the same and move the said inner cutter into and out of position for cutting and to arrange the same to coöperate with either of the cutting edges of the main cutter, said operating means forming a handle for the cake-cutter when the inner cutter is in either position.

4. A cake-cutter comprising an outer or main cutter, a support pivotally mounted within the outer or main cutter, and an inner cutter carried by the support.

5. A cake-cutter comprising an outer or main cutter, an inner pivotally-mounted support normally interlocked with the outer or main cutter and adapted to be reversed, and an inner cutter carried by the support.

6. A cake-cutter comprising an outer resilient main cutter having opposite grooved portions, a pivotally-mounted support interlocked with the grooved portions of the outer cutter, and an inner cutter carried by the support.

7. A cake-cutter comprising an outer or main cutter, a pivoted support mounted within the main cutter, an exterior handle connected with the pivoted support, and an inner cutter carried by the latter.

8. A cake-cutter comprising an outer or main cutter, a pivotally-mounted transverse support interlocked with the main cutter, an exterior handle rigid with the support, and an inner cutter mounted on the support.

9. A cake-cutter comprising an outer or main cutter, a reversible support, a handle connected with the support, and an inner cutter mounted on the support.

10. A cake-cutter comprising an outer or main cutter, a reversible support having an opening, and an inner cutter having its inner end fitted within the said opening and rigidly connected with the support.

11. A cake-cutter comprising a body having a smooth cutting edge and provided with opposite crimped cutting edges, and a reversible inner cutter.

12. A cake-cutter comprising a body having a smooth cutting edge and provided with opposite crimped cutting edges, a reversible inner cutter, and an exterior handle extending from the body between the said cutting edges and connected with the inner cutter for operating the same.

In testimony that I claim the foregoing as my own I have hereto affixed my signature in the presence of two witnesses.

SIMON J. HARDING.
